UNITED STATES PATENT OFFICE.

CASSIUS EUGENE HIATT AND WILLIAM JOSEPH DAVIS, OF LONDON, ENGLAND.
VALVE OF WIRELESS TRANSMISSION SYSTEMS.

1,394,090.

Specification of Letters Patent.

Patented Oct. 18, 1921.

Application filed May 19, 1919. Serial No. 298,261.

(GRANTED UNDER THE PROVISIONS OF THE ACT OF MARCH 3, 1921, 41 STAT. L., 1313.)

To all whom it may concern:

Be it known that we, CASSIUS EUGENE HIATT and WILLIAM JOSEPH DAVIS, a citizen of the United States of America and a subject of the King of Great Britain, respectively, and both residents of London, England, have invented certain new and useful Improvements in Valves of Wireless Transmission Systems, (for which I have filed an application in England April 15, 1918, Patent No. 129,051,) of which the following is a specification.

This invention relates to the valves of wireless transmission systems, and is applicable in particular to War Office R. Navy R4, Navy T and other types of valves.

These valves consist in general of a filament or cathode, which is the generator of the electrons—surrounded by a coiled grid 20 while outside the grid and concentric with it is a sheath or plate forming the anode—which is the collector of the electrons—of gas freed nickel, the whole being contained and supported in a bulb exhausted to a very high degree of vacuum and the present invention concerns the construction of the sheath or anode and its attachment and support to the usual glass support within the bulb usually known as the stem.

As at present constructed the sheath or plate aforesaid is connected by electric welding to the upper end of a metal rod or post which at its other end is embedded in the glass support or stem together with the electrical lead or conductor to which it is connected in the usual way. The process of electric welding is an expensive and difficult operation and moreover tends to introduce joints having variable electric and particularly thermal conduction between the said sheaths or plates and their metal rods or posts. The electric welding process is moreover usually carried out in an atmosphere of hydrogen in order to prevent oxidation and during the process it absorbs the hydrogen and is therefore not gas free. When the spot welding process effected in atmosphere is employed, it will be appreciated that our invention is even more advantageous.

The object of our invention is to provide a structure of increased rigidity in which

there will be a higher thermal conductivity between the sheath or plate and its support and at the same time provide a less expensive process of manufacture than hitherto obtaining, and the invention consists broadly in providing the sheath or plate with an integral extension preferably of curved section adapted to either constitute the support and be directly connected to the electrical lead and embedded in the glass support or stem within the bulb or alternatively to be clamped or compressed into conductive engagement with the metal supporting rod or post to which the lead is connected in the usual way.

In the accompanying drawings Figure 1 is a perspective view of a complete valve, the glass bulb being broken away for convenience of illustration.

Fig. 2 is an end view, and Fig. 3 a side view of the essential elements of the valve, while Fig. 4 is a perspective view of a modification of the invention.

Referring particularly to Figs. 1 to 3, we form the sheath or plate 1 with a narrow ribbon like extension 2 preferably of curved cross section and so located that when the sheath or plate is rolled into its cylindrical form this extension forms the support, its free end being connected to the electrical lead 3 and embedded in the glass support or stem 4 within the bulb 5. The filament or cathode 7 and coiled grid 8 are disposed within the sheath or anode 1 in the usual way, the filament 7 being supported by the legs 9. Alternatively the ribbon extension 2 aforesaid, instead of itself being connected to the lead and embedded in the glass support or stem is wound around or made to embrace the usual metal supporting rod or post 6 and is compressed or clamped into conductive engagement with the post as indicated in Fig. 4 of the drawings. By either method a rigid structure results and the process of electric welding is obviated and there is an increased thermal conductivity whereby the plate support is at an elevated temperature during the usual exhausting process thereby freeing the plate support from detrimental gases in much the same fashion as the plate itself is freed but to a somewhat lesser degree since of

course the support will not attain the same temperature as the plate itself.

What we claim and desire to secure by Letters Patent is:—

- 5 In a valve for wireless telegraph systems including a bulb, an anode in the form of a spirally wound plate having an integral

extension embedded in the glass support within the bulb, said extension supporting said anode and serving for connection to 10 the electrical lead.

In witness whereof we affix our signatures.

CASSIUS EUGENE HIATT.

WILLIAM JOSEPH DAVIS.
